(57) **CLAIM**

The ornamental design for a cooking appliance door, as shown and described.

DESCRIPTION

FIG. 1 is a perspective view of one embodiment of the cooking appliance door showing our ornamental design;

FIG. 2 is a front plan view of the one embodiment of a cooking appliance door shown in FIG. 1;

FIG. 3 is a right plan view of the one embodiment of a cooking appliance door shown in FIG. 1;

FIG. 4 is a left plan view of the one embodiment of a cooking appliance door shown in FIG. 1;

FIG. 5 is a bottom plan view of the one embodiment of a cooking appliance door shown in FIG. 1;

FIG. 6 is a top plan view of the one embodiment of a cooking appliance door shown in FIG. 1;

FIG. 7 is a perspective view of another embodiment of the cooking appliance door showing our ornamental design;

FIG. 8 is a front plan view of the another embodiment of the cooking appliance door shown in FIG. 7;

FIG. 9 is a right plan view of the another embodiment of the cooking appliance door shown in FIG. 7;

FIG. 10 is a left plan view of the another embodiment of the cooking appliance door shown in FIG. 7;

FIG. 11 is a bottom plan view of the another embodiment of the cooking appliance door shown in FIG. 7; and,

FIG. 12 is a top plan view of the another embodiment of the cooking appliance door shown in FIG. 7.
